UNITED STATES PATENT OFFICE.

GUY K. MITCHELL, OF BALTIMORE, MARYLAND

PLUG-SWITCH.

1,112,466.

Specification of Letters Patent. Patented Oct. 6, 1914.

Application filed December 23, 1911. Serial No. 667,485.

To all whom it may concern:

Be it known that I, GUY K. MITCHELL, a citizen of the United States, residing in Baltimore and State of Maryland, have invented certain new and useful improvements in Plug-Switches, of which the following is a specification.

My invention relates to connecting devices for electric circuits, and more particularly to that class of such devices known as plug switches.

The primary object of the invention is to provide a simple and practical plug switch capable of carrying the heavy currents used for driving large motors and the like. To this end, the invention contemplates the provision of improved switch members whereby the intimate contact necessary to good conductivity and efficient operation is obtained.

Other features of my invention consist in providing means for insuring the insertion of the plug always in the same relative position, and means for preventing short-circuiting of the live terminals by a careless handling of the plug.

While my invention is especially adapted for use in connection with three-phase or three wire systems, it is, in certain of its aspects, equally applicable to two wire, or multiple wire circuits.

In order that my invention may be readily understood, reference is had to the accompanying drawings, forming part of this specification, and illustrating, by way of example, the invention as embodied in a plug switch for 3-phase circuits.

In these drawings: Figure 1 is a plan view of the socket member of my improved switch, with the casing shown in section; Fig. 2 is a side elevation of the socket member, the casing being shown in section, substantially on the line 2-2 of Fig. 1; Fig. 3 is an end view of the plug member; Fig. 4 is a side view thereof; Fig. 5 is a detail sectional view of one of the contact blades and its supporting member, the section being taken substantially on the line 5-5 of Fig. 2; Fig. 6 is a similar view showing the parts in the relation which they assume when the plug is in position, and illustrating a fragment of the plug; Fig. 7 is a front elevation of my complete switch as it appears in use; Fig. 8 is a sectional elevation of the complete switch, showing a slightly modified

arrangement, and, Fig. 9 is an end view of the plug member shown in Fig. 8.

In the operation of certain classes of yards and plants, as well as shops, and especially where individual motor drive for the machines has been adopted, it is often desirable to move a machine from place to place and to be able to connect its motor with a source of current supply at any one of a plurality of points. To meet these requirements in a convenient and satisfactory manner, I propose to install at various points throughout the shop or plant socket members or receptacles constituting part of my improved plug switches, and to connect each of such receptacles with the mains.

Referring to the drawings, one of my improved receptacles or socket members is clearly shown in Figs. 1 and 2. It comprises a base 1 of slate or similar insulating material, which is surrounded by a casing 2, provided with a door 3 hinged thereto at 4. The base is provided with screw holes or the like 1^a, by means of which it may be attached to the wall or other suitable support. The door is kept closed at all times when the receptacle is not in use, so as to protect the contact devices. Carried by the base are a plurality of rigid supporting members, three of such members being shown in the drawing, these members being arranged, in this case, in the form of an equilateral triangle. Each of the members is preferably L-shaped and comprises an upright portion 5 and a base portion 6, to the latter of which is attached a binding post 7.

Upon each of the supporting members just described is resiliently supported a contact blade 8, having an outwardly flaring upper end 8^a. This blade is so mounted as to be capable of pivotal movement relative to the supporting member. The preferred method of mounting consists, as clearly shown in Fig. 5, in providing the blade 8 with a plurality of pins or studs 9, 10, rigidly secured thereto, and adapted to project through openings 11 and 12 in the supporting member, such openings being considerably larger than said pins, whereby canting of the pins is permitted. As shown in the drawings, there is preferably provided a single central pin such as 9 adjacent the outer end of the contact blade, and a pair of spaced pins, such as 10, adjacent the inner end thereof. The pin 9 has its outer end

screw threaded and is provided with a nut larger than the opening 11 in the supporting member. A compression spring 14 surrounds the pin 9 between the blade 8 and the support, and a spring 15 surrounds each of the pins 10 between the blade and the support. By this arrangement it will be seen that the plate 8 may have a pivotal movement relative to the support, such movement 10 being possible by virtue of the large opening 11 through which the pin 9 works. It will also be observed that the plate 8 is resiliently supported adjacent its inner end by means of the springs 15, which springs normally 15 serve to maintain the blade in the inclined position shown in Fig. 5 when the plug is withdrawn. The outward movement of the inner end of the blade 8 is limited by the engagement of the pin 9 with the inner 20 and outer edges of the opening 11. In order to positively and efficiently conduct current to the contact blade 8, a flexible conductor or "pig-tail" 16 is provided, and is secured at one end to the blade 8 and at the 25 other end to the binding post 7.

Each of the three blades, shown in Fig. 1, is constructed and connected in the manner just described. While I have shown three of these contact blades, it is obvious that two 30 could be employed to control a two-wire circuit, such blades being then arranged opposite each other. It is also equally obvious that four or more such blades could be employed, if desired, the blades then being arranged 35 along the sides of a corresponding polygon.

In installing my improved receptacles, I connect the binding post 7 to the conductors 26, leading to the mains, such conductors 40 preferably being formed into a cable 25. This cable enters the casing through an opening 2^a, a plurality of such openings being provided at the sides and ends of the box for the sake of convenience the particular 45 opening employed depending upon the direction from which the cable is led.

In Figs. 3 and 4 I have shown an improved plug which is designed to coöperate with the socket member above described. 50 This plug comprises a body portion 17 of insulating material such as wood, having prismatic faces to which are secured contact plates 18, as by means of screws 18^a. Three of such contact plates are shown in the drawing. By reference to Fig. 3 it will be noted that the contact plates 18 are considerably narrower than the width of the faces to which the plates are secured. This results in the insulating material projecting beyond 55 the edges of the plates on both sides so as to effectually separate them and prevent short circuiting. To the outer end of the contact plates 18 are secured connecting eyes 19, which are adapted to receive the terminals 60 22 of the conductors which form the cable

21, such cable passing through the center of a hollow handle 20 which forms an axial continuation of the prismatic body 17. This hollow handle has openings 23 therein through which the ends of the conductors 70 pass, and is provided with a guard flange 24 adjacent such openings. It will be noted that this flange is preferably quite wide, being of a diameter at least equal to that of the body 17, and thus serves to effectively 75 prevent the fingers of the operator from coming into engagement with the contact plates or conductor ends.

When the plug just described is inserted into the receptacle, each of the blades 8 assumes the position shown in Fig. 6, the spring 15 being placed under compression and the pins 9 and 10 assuming a position substantially at right angles to the supporting member 5. It will be seen that the 80 blades 8 as constructed are thus self-aligning, and that they are forced into close engagement with the contact plates throughout their entire length, thus producing a good 85 conducting joint.

In three-phase work it is usually immaterial what angular position the plug occupies in regard to the contact blades, but in cases where it is necessary or desirable that the plug be always inserted in a definite 95 relation I have provided the arrangement shown in Figs. 8 and 9. This consists preferably in providing an unsymmetrical projection, such as 27, on the end of the body 17 of the plug, and in forming a similarly 100 shaped opening, such as 27', in the base 1. In the drawings I have illustrated the projection and opening as of T-shape, but other unsymmetrical shapes might be employed. In fact a mere pin set eccentrically into the 105 plug would perform the same function. If preferred the projection may be secured to the base and the opening formed in the plug. Where the construction shown, however, is employed it is desirable to space the base 1 110 from the bottom 2^b of the casing 2' by means of spacing blocks 1^b as shown in Fig. 8.

In order to take the strain off of the receptacle and to insure the plug going in perfectly straight and true, I support the 115 weight of the cable 21 by means of a hanger, which, as shown in Fig. 7, consists of a chain 28. This chain is attached to the cable adjacent the plug, by means of a clamping ring or wire 29, and is adapted to be engaged 120 by a hook 30 preferably secured to the box or casing itself.

Not only does the provision of a casing 125 serve to protect the contact blades and prevent external objects from coming into accidental engagement therewith, but it also serves to prevent short-circuiting of the contact blades due to careless handling of the plug. In other words, it makes it impossible to present the plug sideways to the receptacle 130

but compels the operator to present it end-wise, in which position, owing to the fact that the insulation projects beyond the contact plates, it is impossible to bridge two of the blades by means of any of the plates.

It will thus be seen that I have provided an efficient plug switch having strong self-aligning contact blades well adapted for carrying the heavy currents met with in practice, and it is thought that the many advantages of my invention will be readily appreciated by those familiar with the requirements of such apparatus.

What I claim is:—

15. 1. In a plug switch, a socket member comprising a base, a plurality of rigid plates mounted in spaced relation on said base and projecting at right angles therefrom, a contact blade supported by each plate, one end of said blade being pivotally connected with the plate at a point remote from said base, and a compression spring inter-

posed between said blade and plate at a point between such pivotal connection and base.

2. A plug switch comprising a socket member having contact blades, a rigid support to which each of said blades is resiliently secured, such securing means comprising a pair of pins carried by each of said blades and located one adjacent each end thereof, said support having openings through which such pins loosely extend, one of said pins having a head incapable of passing through the associated opening, and a coil spring surrounding each of said pins and interposed between the blade and support.

In testimony whereof I affix my signature, in presence of two witnesses.

GUY K. MITCHELL.
